[54] OFFSET TUBULAR STILTS WITH
UNDERLYING HEIGHT ADJUSTABLE
FOOTREST SUPPORTS

ABSTRACT

An improved stilt structure is provided having improved stability. The foot end of each stilt is offset slightly providing better balance and making walking easier. Structurally, the stilt comprises an elongate tubular member having parallel but offset upper and lower sections with a foot rest movably supported on the upper section adjacent to a generally S-shaped curved portion joining the upper and lower sections. A separate clamp member is movably secured to the upper section beneath the foot rest to support the foot rest in different adjusted positions on the upper section.

OFFSET TUBULAR STILTS WITH UNDERLYING HEIGHT ADJUSTABLE FOOTREST SUPPORTS

BACKGROUND OF THE INVENTION

Stilts have long been used as ambulatory devices.

SUMMARY OF THE INVENTION

It is in general the broad object of the present invention to provide a new and improved stilt construction, one which ensures greater stability during walking and greater ease in walking.

BRIEF DESCRIPTION OF THE DRAWING

FIG. 1 is a perspective view showing a pair of stilts of this invention in use.

FIG. 2 is a side elevation partly in section through a stilt embodying this invention.

FIG. 3 is a view taken along the line 3-3 in FIG. 2.

FIG. 4 is a section taken along the line 4-4 in FIG.

2.

DESCRIPTION OF THE PREFERRED EMBODIMENT

In accordance with this invention, I provide suitable length of tubing 6. This can be either circular or square in cross section. The tube includes an upper end 7 and a lower end 8. The upper end 7 is covered by a resilient rubber cap 9. The lower end 8 receives a plug-type member such as a short hexagonal headed bolt covered with a rubber cap 12 to spread the weight over an enlarged area.

A step, generally indicated at 14, is mounted intermediate the ends of the elongated supporting member 6. Step 14 comprises a rectangular piece of wood having a hole therein fitting over the elongated supporting member 6. The step is secured at a desired height above lower end 8 by a clamp structure, generally indicated at 16, and which fits about a resilient member 17 engaged with the support 6. Clamp 16 is of a well-known construction; it is secured in place by rotation of screw 18 in nut 19. The step 14 is maintained in relation to the clamp 16 by a staple 21 provided about the screw 18 and extending into the block.

In accordance with this invention, the bottom end 8 is offset with respect to the upper portion 7, the offset being such that the axis of the bottom section is parallel to the axis of the upper section, the distance separating the two axes being approximately one-half the length of that portion of the step 14 on which the feet of the user rests.

From the foregoing, I believe it will be apparent that I have provided a new and improved stilt design in which offsetting of the lower portion makes the stilts easier to walk with. The resilient tips at both ends create safety, comfort and good appearance. The height of 55

the step being adjustable, the stilt can be accommodated readily to persons of differing heights. The overall design lends itself toward low cost production because most parts are commonly available in mass produced quantities.

I claim:

1. A stilt comprising an elongate tubular member of substantially constant cross-sectional size throughout its length and having a substantially straight lower section and a substantially longer, straight upper section, with the axes of the upper and lower sections parallel and offset from one another, the adjacent ends of the straight upper and lower sections joined by an arcuately curved section of generally S-shaped configuration, a foot rest slidably received on the upper section at a lower end portion thereof adjacent to but spaced upwardly from the arcuately curved section, said foot rest being provided with a top horizontal surface and a bottom horizontal surface and having a hole there-through adjacent one end thereof through which said upper section is slidably received, and a separate clamp member movably secured to said upper section entirely beneath said foot rest and having a top surface secured to said bottom horizontal surface of said foot rest supporting said foot rest on said upper section, said clamp member being adjustably positionable along the length of said upper section to enable said foot rest to be supported at different axially adjusted positions on said upper section.

2. A stilt as in claim 1, wherein the foot rest is rectangular and the top and bottom horizontal surfaces thereof are parallel to one another, said hole having a length between the top and bottom horizontal surfaces substantially greater than the cross-sectional thickness of the upper section of the tubular member.

3. A stilt as in claim 2, wherein said foot rest comprises a block of wood.

4. A stilt as in claim 1, wherein said clamp member includes an arcuate portion extending around said upper section beneath said foot rest, a nut supported by said clamp member, and a screw threaded through said nut and into engagement with a clamping plate to clamp said upper section between said arcuate portion and said clamping plate.

5. A stilt as in claim 4, wherein a resilient member is engaged between said upper section and said arcuate portion and said clamping plate.

6. A stilt as in claim 1, wherein fastening means extends from said clamp member into said bottom horizontal surface of said foot rest to secure said foot rest to said clamp member.

7. A stilt as in claim 1, wherein a resilient cap is on the upper and lower ends of the stilt.
